RESERVOIR PEN

Filed Jan. 17, 1929

Inventor:—

Horace Roderic Hughes
by George E. Lakes,
his Attorney.

UNITED STATES PATENT OFFICE

HORACE RODERIC HUGHES, OF ALCESTER, ENGLAND

RESERVOIR PEN

Application filed January 17, 1929, Serial No. 333,061, and in Great Britain March 24, 1928.

This invention relates to reservoir pens, and has for its object to provide a reservoir pen nib simple in construction and efficient in use.

5 The invention consists in the provision in combination with a pen nib and contiguous to the longitudinally extending middle slit and/or piercing in the anterior section of the nib and on the lower or underside thereof 10 of a plurality of longitudinally extending fins or webs.

Preferably two such fins or webs are provided spaced apart and parallel or substantially parallel with each other, one being 15 located on each side of the slit and/or piercing on the middle line of the nib. The rear ends of the said fins or webs may be in line with the posterior end of the middle slit and/or piercing of the nib or they may terminate at 20 a point in front of or to the rear of the posterior end of the slit and/or piercing as may be desired.

The webs or fins may be obtained by stamping and bending operations from a blank of 25 thin sheet metal and are provided at the posterior ends thereof with means whereby they are securely attached to the body of the nib.

The invention will be further described 30 with reference to the accompanying drawings, wherein:—

Figure 1 represents, in plan of lower or underside, a pen nib provided with fins or webs in accordance with the invention.

35 Figure 2 represents the same partly in longitudinal section and partly in side elevation.

Figure 3 is a cross sectional view on the plane indicated by the dotted line 3—3, Figure 2.

40 Figure 4 is a similar view to Figure 3 on the plane indicated by the dotted line 4—4, Figure 2.

Figure 5 illustrates a conveniently shaped 45 and pierced blank from which by pressing and bending operations the fin forming member may be obtained.

Figures 6 and 7 represent the said blank in 50 side elevation and plan respectively after the same has been submitted to the requisite bend-

ing operations for bringing it into the form in which it is applied to the pen nib.

Figure 8 is a similar view to Figure 1 of a modified construction of reservoir fitment hereinafter more particularly referred to. 55

Figure 9 is a cross section on the plane indicated by the dotted line 9—9, Figure 8.

Figure 10 represents in plan the blank from which the said modified reservoir fitment is obtained, and 60

Figure 11 shows the modified reservoir fitment detached in side elevation.

The same numerals of reference indicate the same or corresponding parts in the several figures of the drawings. 65

Describing first the embodiment of my invention illustrated by Figures 1 to 7, both inclusive, of the drawing 12 and 12^a denote the anterior and posterior parts of the pen nib to which the invention is applied, the anterior 70 part having as usual the middle slit and/or piercing 12^b. On the lower or underside of the said anterior portion 12 and disposed preferably symmetrically one on each side of the middle slit or piercing 12^b are the longitudinally extending fins or webs 13, the said fins or webs being in the main parallel or substantially parallel. The upper edges of the fins or webs 13 that is to say the edges which are presented to the underside of the anterior 75 part 12 of the nib lie flush or practically flush therewith and preferably the said edges are interconnected by a transverse web, or webs, 13^c formed integral therewith and serving to preserve the interconnected edges at the desired distance apart and give rigidity thereto, but if desired such interconnecting web or webs may be dispensed with. 85

In providing the said fins or webs 13 I take a blank of sheet metal of suitable contour and dimensions, as for example, the contour represented in Figure 5, the said blank being provided either in the stamping operation whereby it is obtained, or by a subsequent operation, with the slots or apertures 13^b, 13^c and 13^d 95 leaving the parts 13^a to form the interconnecting webs hereinbefore referred to.

The blank Figure 5 terminates at one end in an unslotted part 13^e having laterally extending ear pieces or wings 13^f which serve as 100

hereinafter described in the attachment of the fins to the pen nib.

By a suitable pressing or bending operation or operations the parts of the blank on either side of the slotted middle part are brought into vertical or substantially vertical planes so as to lie parallel or substantially parallel with each other, as best seen in Figure 3, and the adjoining unslotted part 13^e is given a configuration the counterpart of that portion of the nib against which it fits when the blank is applied to the underside of the nib with the fins or webs 13 disposed in the desired position relative to the anterior portion 12 of the nib and the middle longitudinal slit and/or perforation 12^b therein. At the same time the ear pieces or wings 13^f are or may be bent to the position in which they are represented in Figures 6 and 7, so as thereby to form clip-like parts adapted when the fin or web forming blank is applied to the nib to grip and overlap the adjacent parts thereof as is best seen in the section Figure 4.

The front ends of the wings 13 are or may be made divergent as shown in Figures 1 and 7.

The edges of the nib at the parts which when the fin or web forming blank is applied thereto are overlapped by the said ear pieces or wings 13^f are formed with slight recesses or depressions which provide shoulders or abutments 12^e and 12^d (see Figure 2) serving definitely to locate the ear pieces on the nib body and prevent longitudinal displacement of the webs or fins 13 in a rearward direction or, if desired, in either direction. The prevention of forward motion however and the very secure retention of the web or fin blank in place is ensured providing the body of the nib with a tongue-like part 12^e which, by a suitable slitting and pressing operation, is depressed therefrom into such location on the underside or face of the nib that it can engage below the underside of the fin or web blank preferably at or about the part thereof at which the posterior ends of the fins or webs adjoin the extension 13^e on which the ear pieces or wings 13^f which clip the respective sides of the nibs are provided. The tongue-like part 12^e is so depressed from the body as to form a sharp shoulder 12^f (see Figure 2) at its junction therewith, which shoulder forms a definite abutment for the edge of the fin blank which is presented thereto when the said blank is properly positioned on the nib, the shoulder serving definitely to locate the position of the fin or web blank. The front or free end of the tongue-like part is slightly bent or turned down to provide a lip which guides the web or fin blank into its engaging position with the tongue member, the fin or web blank being suitably slotted to permit the tongue 12^e to pass therethrough and engage below the same. When this engagement

has been effected and the fin blank pushed against the shoulder 12^f of the tongue the rear part of the fin blank engages with the shoulders 12^e and 12^d formed by the slight recesses or depressions in the sides of the nib and the fin or web blank is very effectively restrained from longitudinal motion in either direction.

Further, the engagement of the tongue member 12^e below the lower face of the web or fin blank serves to clip the said blank closely against the underside of the nib and retain the edges of the webs or fins which are presented to the underside of the nib in close contact therewith.

I wish it to be understood that I do not limit myself to any particular shape or contour of the nib body nor to the precise construction of the parts described as the same may be varied without departing from the invention, for example, the webs 13 instead of being of substantially the same depth from front to back as shown may vary in depth from front to back the ends thereof adjacent the point of the nib rising from the nib without the formation of a definite shoulder or front edge.

Further, if desired the longitudinal edges of the webs or fins 13 may be furnished, as is shown in Figure 8, with ear pieces or wings 13^g formed on the longitudinal edges thereof remote from the underside or face of the nib and bent laterally outward, that is to say, in a direction toward the respective sides of the nib, the said ear pieces or wings being preferably disposed at or adjacent the posterior ends of the fins or webs 13.

A cross section of this modification on the plane indicated by the dotted line 9—9, Figure 8, is shown in Figure 9.

Figure 10 shows the blank from which the said modified fitment is formed and Figure 11 is a side elevation of the said fitment detached from the body of the nib.

By the improvements described a reservoir pen nib simple in construction and very efficient in use is provided, and further the three point attachment of the web or fin blank to the nib, constituted by its engagement with the depressed tongue 12^e and of its wings 13^f with the edges of the nib serves very effectually to retain the webs or fins in the desired position relative to the nib.

What I claim is:

A reservoir pen nib comprising a separate member adapted to be disposed on the underside of the anterior portion of the nib, a plurality of substantially parallel webs formed integral with the said member and constituted by slitting the said member and bending the marginal portions of the slit sections through angles of approximately 90° so that the webs are arranged edgewise relatively to the nib and with their upper edges in substantial abutment with the underside of the

anterior portion of the pen nib, transverse means located intermediate the ends of the webs and connecting the outer edges thereof, a rear extension of the said member shaped to conform to the part of the nib to which it is adjacent, a cut away portion adjacent to the said shaped rear portion of the aforesaid member, a centrally disposed downwardly bent tongue pressed out of the nib and adapted to engage with the said cut away portion, and ear pieces formed integral with the said rearward extension and adapted to be bent round the nib for securing the aforesaid member thereto, said ear pieces in conjunction with the aforesaid tongue constituting a three point attachment means for the said member which ensures the correct positioning thereof relatively to the nib.

In testimony whereof I have signed my name to this specification.

HORACE RODERIC HUGHES.
